UNITED STATES PATENT OFFICE.

FRANK J. CANDEE, OF LITTLE BLUE, MISSOURI.

DESIGN FOR A GAME-BOARD.

SPECIFICATION forming part of Design No. 26,042, dated September 15, 1896.

Application filed June 8, 1896. Serial No. 594,796. Term of patent 3½ years.

To all whom it may concern:

Be it known that I, FRANK J. CANDEE, of Little Blue, Jackson county, Missouri, have invented a new and useful Design for a Game-Board, of which the following is a full, clear, and exact description, reference being had to the accompanying drawings, forming a part thereof.

The leading feature of my design is the peculiar arrangement of cavities or holes in a board or base of circular form.

Figure 1 represents a plan view of the same. Fig. 2 represents a cross-section of the same, taken through its center.

Referring to said drawings in detail, 1 designates a circular board or base of wood or any other suitable material, and 2 cavities or holes in the upper side of the same. Said cavities or holes are arranged in the form or

outline of a true cross, substantially as shown 20 in Fig. 1, and are thirty-three in number. The base marginally is also provided with an upwardly-projecting annular flange 3 and in its under side with a rectangular cavity 4, the configuration of said cavity being represented 25 by dotted lines in Fig. 1.

Having thus described my invention, what I claim as new, and desire to secure by Letters Patent, is—

The design for a game-board, substantially 30 as herein shown and described.

In testimony whereof I affix my signature in presence of two witnesses.

FRANK J. CANDEE.
